MOTOR DRIVEN HANDLE FOR A TOOTHBRUSH

Ulysses S. Mozneck, Trumbull, Conn., assignor, by mesne assignments, to Scovill Manufacturing Company, Waterbury, Conn., a corporation of Connecticut

Filed July 31, 1963, Ser. No. 76,057

Term of patent 14 years

(Cl. D9—2)

Fig. 1

Fig. 2

Fig. 3

Fig. 4

Fig. 5

Fig. 6

FIGURE 1 is a front view of a motor driven handle brush showing my new design;

FIG. 2 is a side view thereof;

FIG. 3 is a back view thereof;

FIG. 4 is a top view thereof; and

FIG. 5 is a bottom view thereof.

FIG. 6 is a cross sectional view taken horizontally through the facets at the bottom of the head portion of the handle.

I claim:

The ornamental design for a motor driven handle for a toothbrush, as shown.
